METHOD AND APPARATUS FOR TUBE EXPANSION

Harold C. Mathews, Springfield, Ohio, assignor to The Airetool Mfg. Co., Springfield, Ohio, a corporation of Ohio

Application September 14, 1950, Serial No. 184,743
13 Claims. (Cl. 29—157.5)

This invention relates to apparatus for expanding tubes into tube sheets such as in condensers and other heat exchangers.

An object of the invention is to provide a tube expander of an improved form by which the degree of expansion of the tubes can be accurately controlled, and particularly wherein the same degree of expansion can be given to a number of tubes of like diameter and like wall thickness.

Another object of the invention is to provide a tube expander wherein the degree of expansion of a tube along the length of its contact with the tube sheet is maintained uniform with a uniform degree of reduction of tube wall thickness throughout the length of the contact of the tube with the tube sheet.

Still another object of the invention is to provide a tube expander with a central mandrel that is driven in one direction to place the expanding rolls into contact with the tube for expanding the same and is driven in an opposite direction to cause withdrawal of the expander from the tube with simultaneous expansion of the tube into engagement with the tube sheet.

Still another object of the invention is to provide a tube expander in accordance with the foregoing objects wherein the expansion of the tube is carried forward from the inner face of the tube sheet toward the outer face of the tube sheet.

Still another object of the invention is to provide a tube expander which includes a device to control the position of the expanding rolls of the expander within a tube so that the rolls can be positioned within a series of tubes sequentially at exactly the same depth, and also to provide a device for controlling the position of the mandrel relative to the rolls for regulating the position of the rolls to obtain exactly the same degree of radial expansion in each of the series of tubes.

Another object of the invention is to provide means operating in cooperation with the tube expander to indicate the degree of expansion of a tube in a tube sheet so that a series of tubes in a tube sheet can each be expanded individually with a like degree of expansion into engagement with the tube sheet irrespective of dimensional variations of the tube and the hole in the tube sheet receiving the tube.

Still another object of the invention is to provide a method of expanding tubes into a tube sheet by which the tube is placed under tension at the beginning of the tube expanding operation to thereby prevent buckling of the tube between tube sheets placed at opposite ends of the tube.

Another object of the invention is to provide a method of expanding a tube into a fluid-tight bond with a tube sheet in which the tube is initially expanded into engagement with the tube sheet in proximity of the inner face of the tube sheet with resultant reduction in wall thickness of the tube, the expansion causing the tube to be initially placed under tension before reducing the wall thickness of the tube, which tension is thereafter at least partially released by the resultant flow of metal in the tube in both directions axially of the tube.

It is still another object of the invention to provide a method of expanding a tube into a fluid-tight bond with a tube sheet in accordance with the foregoing object

2

wherein, after the tube is given its initial expansion in proximity of the inner face of the tube sheet, the tube is expanded in one continuous operation from the inner face of the tube sheet toward the outer face thereof resulting in a reduction in wall thickness of the tube and resultant flow of metal in the tube axially thereof from the inner face of the tube sheet toward the outer face thereof, which is the direction of least resistance to the flow of metal in the tube.

10 Further objects and advantages will become apparent from the drawings and the following description.

Figure 1 is a longitudinal cross-sectional view of a tube expander incorporating features of this invention;

15 Figure 1a is an elevational view partially in section illustrating the position of the tool of Figure 1 in the first step of expanding a tube into a tube sheet and wherein the tool and tube are positioned loosely in the seat of the tube sheet.

Figure 1b is a view similar to that of Figure 1a illustrating the position of the tool in the second step of expanding a tube into a tube sheet and wherein the interior portion of the tube has been expanded against the tube seat by the expanding tool.

20 Figure 1c is a view similar to that of Figure 1a illustrating the position of the tool in the third and final step of expanding a tube into a tube sheet with the tool being moved outwardly of the tube and wherein the tube has been expanded into contact with the tube seat over a portion of the length thereof from the interior face of the tube sheet outwardly.

Figure 2 is an elevational view of a portion of the cage of the tube expander illustrating the rolls of the tube expander as set at a self-feeding angle;

Figure 6 is a cross-sectional view taken along line 6—6 of Figure 5;

35 Figure 7 is a cross-sectional view taken along line 7—7 of Figure 5;

Figure 8 is a composite elevational and cross-sectional view illustrating the first step in the method of using the tube expander shown in Figure 5;

40 Figure 8a is a view of a portion of Figure 8 with the parts broken away.

Figure 9 is a view similar to Figure 8 illustrating the expanding step in the method of tube expansion using the tool of Figure 5;

45 Figure 10 is a view similar to Figure 8 illustrating the completion of the method of expanding a tube.

Figure 11 is an elevational view of a driver and a control for operating the tube expanders illustrated in Figures 1 and 5.

The tube expander of this invention illustrated in Figures 1, 2 and 3 consists of a tube expanding head 10 that has a longitudinal bore 11 extending axially through the cage. The cage 10 has radially disposed slots 12, 13 and 14 (Fig. 4) each of which receives a roll, 15, 16 and 17, respectively. The slots, 12, 13 and 14 are shaped to prevent the rolls 15, 16 and 17 from leaving the slots radially of the cage 10, the outer ends of the slots being narrower than the diameter of the rolls.

50 The rolls 15, 16 and 17 are set at an angle relative to the axis of the cage 10, as illustrated in Fig. 2, whereby the rolls self-feed a mandrel 20 that extends axially through the bore 11, inwardly of the cage 10 upon rota-

tion of the mandrel in one direction and upon reversal of rotation of the mandrel the rolls self-feed the cage outwardly through a tube that is being expanded.

The mandrel 20 is provided with a long forward tapered end that engages the rolls 15, 16 and 17 to selectively position them radially outwardly of the cage 10 when the forward end of the cage is placed within a tube. The rolls 15, 16 and 17 are tapered between their opposite ends to match the tapered end of the mandrel 20. Also, the rolls 15, 16 and 17 each have their opposite ends 18 and 19 tapered to thereby eliminate formation of a spiral ridge on the inner surface of a tube as the expander self-feeds itself through the tube.

The rear end of the mandrel 20 has a threaded portion 21 that engages the internal thread 22 of the housing 23. A longitudinal groove 24 extends along the threaded portion 21 of the mandrel 20 to receive the end of a set-screw 25 to lock the mandrel 20 to the housing 23 after suitable adjustment has been made between these members.

The forward end of the housing 23 has a radially flanged head 26 that is received within a rotatable collar 27, the flanged head 26 of the housing 23 engaging an inwardly flanged portion 28 on the collar 27 which prevents removal of the housing 23 from the collar 27 in a leftward direction as viewed in Figure 1. The collar 27 also has a bayonet lock slot 30 (Fig. 3) in diametrically opposite sides thereof and each of which slots is adapted to engage lock pins 31 extending from the collar 32; the collar 32 is secured to the cage 10 by means of a set-screw 33. The housing 23 has an end portion 34 adapted for engagement by a chuck of a suitable driving device and a ring 23a secured on the housing protrudes slightly above the housing surface between end portion 34 and flange head 26; this ring is not necessary to the operation but may be utilized to retain rotatable collar 27 on the housing when the collar is disengaged from pins 31. It is thus to be noted that the mandrel 20 and the housing 23 are threadedly engageable and are retained fixedly in a desired engaged position by set screw 25. Accordingly housing 23 and mandrel 20 in their operative position are locked against relative axial movement but are rotatable together as a unit.

The collar 27 carried by housing 23 is engageable with pins 31 carried by the collar 32 (Figures 1 and 3); the collar 32 is secured to cage 10 and hence in the engaged position of collar 27 and pins 31 the cage 10, housing 23 and mandrel 20 are locked together for rotation as a unit, if set screw 25 is tight on the mandrel 20. Also the mandrel and cage are then locked against relative axial movement in either direction of rotation of the mandrel and housing.

To permit free rotation of the housing and mandrel with respect to cage 10, as well as longitudinal movement of the same with respect to the cage, it is only necessary to release the collar 27 (Figure 1) from the pins 31 and move the collar 27 leftwardly on the housing 23, free of the pins carried by collar 32 (Figure 1a).

The use of the structure of Figure 1 in securing a tube in tube sheets will now be described in detail in connection with Figures 1a, 1b and 1c, and for the purposes of description it will be assumed that a first end of the tube has been secured in a tube seat of a first tube sheet and the second end of the tube is about to be secured in a tube seat of a second tube sheet 101'.

Initially, in using the embodiment described, the collar 27 is released (Figure 1) from pins 31 to position the collar 27 freely on housing 23; the mandrel 20 is then threaded into the housing 23 to the desired position and set screw 25 secured, thus locking the housing 23 and mandrel 20 fixedly together, the two being rotatable with respect to, and also longitudinally movable with respect to cage 10. Nut 44 prevents complete withdrawal of the mandrel from the cage in one direction while the rolls 15 and housing 23 prevent complete withdrawal of the mandrel in the other direction.

With nut 44 against the end of cage 10 and the rolls thus in a contracted position, the cage is inserted into the tube 100' (Figure 1a) until the rolls are at the inside face of the tube sheet; at this time the tube 100' is of course only loosely positioned within the tube seat.

The stop member 35 is now threaded along cage 10 until it engages the outer face of the tube sheet; the stop member is then secured in position by set screw 37 and thus further entry of the cage 10 into the tube seat is inhibited (Figure 1a). Mandrel 20 is then urged rightwardly through the positioned cage to contact the rolls 15.

A reversible driver, such as that indicated in Figure 11, secured to the end portion 34, is rotated then in a clockwise direction and the mandrel 20 also rotates in a clockwise direction as indicated by the arrow (Figure 1b) in engagement with the rolls 15 and due to the self-feeding relationship the mandrel feeds through the rolls further, causing the same to expand against the loosely retained tube 100'.

In this initial expansion period the tendency is for cage 10 to also feed into the tube 100' but since it is restrained by the stop member the tube 100', due to the reaction, feeds outwardly of the sheet (Figure 1b) thus placing an initial tension on the tube 100' between tube sheets. As the expansion of the rolls 15 continues with the feeding of the mandrel the tube 100' engages the seat and the thickness of the tube wall is diminished; this causes metal flow inwardly of and outwardly of the tube seat (Figure 1b) and this inward flow of metal offsets tensile stress occasioned by the initial tensioning action.

The rotation of the mandrel 20 is continued in a clockwise direction until the tube is firmly against the tube seat.

With the inner portion of the tube firmly against the seat the flange 26 of the housing 23 abuts the cage end as shown in Figure 1b; the collar 27 which up to this time has been disengaged is then engaged with pins 31 and the cage housing and mandrel are locked for rotation as a unit.

The reversible driver is now reversed in its rotational direction and the mandrel 20 is driven counterclockwise as per the arrow (Figure 1c); the locking of the mandrel to the cage provides that the mandrel may not move axially with respect to the cage in this direction of rotation and therefore the rolls 15 remain in their expanded position and the entire expander self feeds outwardly of the tube expanding the tube over the length thereof (Figure 1c).

A particular feature of the embodiment of Figure 1, relating to the position of the mandrel 20 with respect to the rolls 15, is that when once adjusted the adjustment may be maintained exactly and resetting is not necessary in order to expand a plurality of similar tubes. Thus to repeat the expansion operation described above it is only necessary to slip collar 27 from pins 31 and to retract the mandrel until nut 44 abuts cage 10. The device may be then inserted in the next tube and the operation repeated.

Surrounding the cage 10 there is provided a stop member 35 having one portion 36 thereof secured to the cage 10 by means of a set-screw 37 that engages a longitudinal groove 38 provided in the threaded extension 39 of the cage 10. The other part 40 of the stop member 35 is secured to the part 36 by means of a C ring 41. The anti-friction ball bearing structure 42 is placed between the parts 36 and 40. The part member 40 is adapted to engage the outer face of a tube sheet to resist movement of the cage 10 into a tube beyond a predetermined depth and is provided with an axial bore 43 which is adapted to receive the end of a tube that may project from the tube sheet. The mandrel 20 has a nut 44 on the end thereof that projects from the cage 10 to prevent the mandrel from being removed from the cage.

In Figures 5, 6 and 7 there is illustrated another form of tube expander incorporating features of this invention. This form of the invention includes a cage 10a con-

structed like the cage 10 illustrated in Figure 1. It also includes the same rolls illustrated in the forward end of cage 10. The cage 10a has a stop member 50 that performs the same function as the stop member 35 and includes a recess 51 to receive the end of a tube projecting from a tube sheet. The stop member 50 has a setscrew 52 to fix it in position on the cage 10a.

A mandrel 55 extends through the bore 11a of the cage 10a in the same manner of the mandrel 20, and cooperates with the rolls of the expander in the same manner as described with reference to Figure 1. The mandrel illustrated in Figure 5, however, is provided with a square head 56 on the rear end thereof for placement within a plug 57. The set-screw 58 retains the square head 56 within the plug 57.

The plug 57 forms a part of a mandrel driver or driving device 60. The driving device includes a housing 61 having a splined internal bore 62 extending axially of the housing 61. The plug 57 is provided with external splines that cooperate with the internal splines of the bore 62 to permit the plug to move axially of the housing 61.

The housing 61 is provided with slots 63 and 64 on diametrically opposite sides thereof which receive a pin 65 projecting from opposite sides of the plug 57. The pin 65 is held in the plug 57 by means of a cross fastening pin 66.

Opposite ends of the pin 65 project through the slots 63 and 64 into engagement with a collar 67 including annular rings 67a that surround the housing 61 and are freely slideable thereon.

The housing 61 is provided with an exteriorly threaded portion 68 which receives a nut 69. The nut 69 provides a stop for the collar 67 to prevent leftward movement thereof on the housing 61.

A plug 70 is suitably secured within the end of the housing 61 and has a projection 71 to which a chuck can be attached for driving purposes. The plug 70 is also provided with a tapered bore 72 to receive a tapered pin of a driving device.

The cage 10a is threadedly received in one end of a sleeve 75 that extends through an opening 76 in a closure cap 77 which is threaded onto the housing 61. The sleeve 75 has a radial flange 78. An anti-friction bearing 79 is placed between the flange 78 and the closure cap 77 and acts as a thrust bearing.

The tube expanders illustrated in Figures 1 and 5 perform a method of tube expansion that is more clearly illustrated in Figures 8, 9 and 10, the device of Figure 5 being used for the purpose of illustrating the expansion of the end of a tube 100 into a tube sheet 101. The tube sheet has an opening 102 which receives the end of a tube 100.

When the tube expander is to be placed into the tube 100, the nut 69 on the housing 61 is backed off to the left as shown in Figure 8 to allow movement of the collar 67 in a leftward direction, thus withdrawing the mandrel 55 from within the cage 10a to permit the rolls in the cage to ride upon the smallest diameter of the mandrel 55. This places the expanding rolls at or below the surface of the cage 10a, and the rolls may be considered as contracted.

The cage 10a with the rolls in the contracted position is then inserted into the tube 100, which tube has previously been placed in the tube sheet 101. The stop member 50 is threaded upon the cage 10a to place the expansion rolls within the tube 100 to the desired depth, as illustrated in Figure 8, that is, with the stop member engaging the outer face of the tube sheet. The set-screw 52 is then tightened to hold the stop member in position on the cage 10a.

A suitable reversible driver is connected to the projection 71 of the tube expander and drives the mandrel 55 in a clockwise direction. The collar 67 is moved axially over the housing 61 in a rightward direction to advance the mandrel 55 into the cage 10a until the expansion rolls

engage the internal diameter of the tube 100, thereafter, continued clockwise rotation of the mandrel causes the mandrel to be fed into the cage 10a by reason of the self-feeding angle at which the rolls 15, 16 and 17 engage the mandrel. This operation continues until the tube 100 is expanded to the desired degree, whereupon the nut 69 is advanced against the collar 67, as shown in Figure 9.

During the self-feeding of the mandrel into the tube and the initial expansion of the tube 100, the stop member 50 prevents advancement of the cage 10a into the tube. When the rolls 15, 16 and 17 engage the tube 100 continued clockwise rotation of the mandrel 55 continues the self-feeding of the mandrel between the rolls with resultant expansion of the tube 100 into engagement with the tube sheet. Since the cage 10a cannot be drawn into the tube 100, the reaction of the rolls on the tube causes the tube 100 to be drawn in a leftward direction with the result that a tension is placed upon the tube while it is expanded into engagement with the opening 102 in the tube sheet 101, as illustrated in Figure 9. This preliminary tensioning of the tube between tube sheets after the tube has been expanded into engagement with the one tube sheet prevents buckling of the tube under compression between tube sheets while the opposite end of the tube is being expanded into engagement with the other tube sheet.

With the tube 100 under tension at the time it makes initial engagement with the tube sheet, initial reduction of the wall thickness of the tube causing metal flow in opposite axial directions in the tube will not cause buckling of the tube between tube sheets but will merely release the tension under which the tube has been placed during the first portion of the initial expansion.

The recess 51 in the stop member 50 provides for movement of the end of the tube 100 from the tube sheet 101 during the initial tensioning movement of the tube relative to the tube sheet, and also provides for taking care of any variation in length of the tube between opposite tube sheets as a result of manufacturing tolerances, and also takes care of movement of the tube 100 during the initial expansion into engagement with the tube sheet.

With the tube expander in the position illustrated in Figure 9, the driver is then reversed in its direction of rotation causing the mandrel 55 to be rotated in a counter-clockwise direction. This rotation of the mandrel in the counter-clockwise direction tends to drive the mandrel in a leftward direction through the cage 10a, but this is prevented at this time because the collar 67 abuts the nut 69. Therefore, the counter-clockwise rotation of the mandrel will cause rotation of the rolls and of the cage 10a within the tube 100 with the result that the self-feeding angle at which the expansion rolls 15, 16 and 17 are set will cause the expander head to self-feed from the inner toward the outer surface of the tube sheet 101 with simultaneous expansion of the tube uniformly throughout the length expanded in a continuous operation. With the tube initially expanded into engagement with the tube sheet adjacent the inner face of the tube sheet, flow of metal in the tube resulting from reduction of wall thickness during the expansion operation will be continuously outwardly toward the outer face of the tube sheet, this being the path of least resistance for the metal flow.

At the end of the tube expansion operation, as illustrated in Figure 10, the nut 69 is rotated to move in a leftward direction on the housing 61 so as to release the collar 67 for movement to the position illustrated in Figure 8, whereupon the tube expander can be placed in another tube and the operation repeated.

While the mandrel 55 has been described as being self-fed between the expansion rolls, yet the mandrel can be fed manually or by other mechanism. Also, suitable mechanism can be provided to draw the cage outwardly through the tube 100 for the expansion operation without departing from the method of tube expansion disclosed herein.

In Figure 11, here is illustrated a driver 110, consisting of conventional reversibly rotatable electric motor, the driver being suitably constructed for hand holding. The driver 110 is provided with a chuck 111 into which either of the tube expanders of Figure 1 or Figure 5 can be placed. The electric motor of the driver 110 receives electric current through a control apparatus 112 which measures the amount of current used by the electric motor, a suitable ammeter 113 being provided on the control 112 to indicate the current being supplied to the motor. A control device 114 may be provided to cut off the electric current to the electric motor when the current supplied to the motor reaches a certain value.

Since it is a well-known fact that the amount of electric current used by an electric motor is governed by the torque required to drive a given device under load, the amount of torque that is required to drive the mandrel 20 in the initial phase of expanding the tube will reflect itself in terms of amperes on the ammeter 113 of the control 112. Thus, a determined amount of expansion of a tube of given diameter will require a given consumption of electric current. Thus, by controlling the maximum current that can be used by the electric motor in the initial phase of tube expansion, control of the maximum amount of tube expansion that can be occasioned by the tube expander under a given set of conditions is obtained, since the torque required by the mandrel 20 reflects the force required to expand the tube to a predetermined degree of expansion when the tube is of a given diameter, and of a given material and is being expanded within a tube sheet of a given material. Such a control will expand the tube into engagement with the tube sheet with a predetermined pressure to give a satisfactory bond to the tube sheet without over-stressing the tube or reducing tube wall thickness unnecessarily. A fluid-operated motor and suitable control, therefore, can be used in place of the electric apparatus.

Thus, by making the initial expansion of a tube under control of the apparatus 112, an operator can give to each individual tube individual treatment with the result that each tube will be expanded to exactly the same degree of expansion and pressure engaging the wall of the tube sheet irrespective of dimensional variations of the tube and of the openings in the tube sheet.

While the invention as disclosed and described herein illustrates preferred forms of apparatus and a method of expanding tubes, it will be understood that modifications can be made without departing from the spirit of the invention, and that all modifications that fall within the scope of the appended claims are intended to be included herein.

I claim:

1. A tube expander comprising, a cage having a plurality of rolls positioned about the same with their axes positioned angular to the axis of said cage, a tapered mandrel positioned axially within said cage reversibly rotatable therein and engaging said rolls for radial movement thereof in said cage upon axial movement of said mandrel in said cage whereby said rolls may be expanded and contracted, a housing rotatably mounted with respect to said cage and releasably secured against longitudinal movement with respect thereto, said housing having an end portion of said mandrel secured therein for rotation therewith, said mandrel and housing being rotatable in one direction to move said rolls into an expanded position, said housing and cage having means cooperating to lock said housing, mandrel and cage against relative axial movement in the other direction of rotation of said mandrel in the expanded position of said rolls.

2. A tube expander comprising a cage having a plurality of rolls positioned about the same with their axes positioned angularly to the axis of said cage, a rotatable mandrel within said cage and having a tapered portion engaging said rolls for radial movement thereof upon axial movement of said mandrel whereby said rolls may

be expanded and contracted, stop means on said cage movable thereon to restrict the depth of entry of said head into a tube, a housing rotatably secured to said cage against longitudinal movement with respect thereto and having an end portion of said mandrel received therein, means securing said mandrel to said housing for longitudinal movement therein and rotation therewith, said mandrel and housing being rotatable in one direction to move said rolls into an expanded position in the engaged position of the stop means, and means on said housing longitudinally movable therealong and engageable with said securing means to lock the same and said mandrel in one direction of axial movement of said mandrel, said housing and mandrel being rotatable in the opposite direction in the expanded position of said rolls and in the engaged positions of said longitudinally movable means and said stop means whereby said cage, mandrel and housing are axially movable as a unit.

3. In a tube expander the structure comprising a cage having a plurality of radially movable rolls therein, a tapered, axially movable mandrel, rotatable clockwise and counter-clockwise, in contact with said rolls at an angle therewith for self-feeding of the mandrel through the cage whereby said rolls may be expanded and contracted, said mandrel being rotatable in one direction to move said rolls into an expanded position, and means to lock said mandrel and cage against relative axial movement in the other direction of rotation of said mandrel in the expanded position of said rolls.

4. In a tube expander the structure comprising a cage having a plurality of radially movable rolls therein, a tapered, axially movable mandrel, rotatable clockwise and counter-clockwise, in contact with said rolls at an angle therewith for self-feeding of the mandrel through the cage whereby said rolls may be expanded and contracted, said mandrel being rotatable in one direction to move said rolls into an expanded position, a housing having an end portion of said mandrel received therein, means to secure said end portion and said housing together for rotation of said mandrel and housing as a unit, and means, including said housing, to lock said mandrel and cage against relative axial movement in the other direction of rotation of the said mandrel in the expanded position of the rolls.

5. In a tube expander the structure comprising a cage having a plurality of radially movable rolls therein, a tapered, axially movable mandrel, rotatable clockwise and counter-clockwise, in contact with said rolls at an angle therewith for self-feeding of the mandrel through the cage whereby said rolls may be expanded and contracted, said mandrel being rotatable in one direction to move said rolls into an expanded position, a housing secured against longitudinal movement with respect to said cage and having an end portion of said mandrel secured therein for rotation of said mandrel and housing as a unit, and means to lock said mandrel and cage against relative axial movement in the other direction of rotation of said mandrel in the expanded position of said rolls.

6. In a tube expander, in combination with a cage having a plurality of movable rolls and a tapered mandrel passing axially through the cage in contact with the rolls at an angle therewith for self-feeding of the mandrel upon rotation thereof, said mandrel being rotatable in one direction to move said rolls into an expanded position, an exteriorly threaded, slotted housing having an axially movable plug splined therein, said housing being rotatable relative to said cage and secured against longitudinal movement with respect thereto, slideable means on and passing through said slotted housing and secured in said plug, said plug also having an end portion of said mandrel secured therein for movement therewith, and a collar threaded on said housing and engageable with said slideable means to restrict the movement of said slideable means, said plug and said mandrel in an axial direction in an expanded position of the rolls.

7. In a tube expander, in combination with a cage

having a plurality of movable rolls and a tapered mandrel passing axially through the cage in contact with the rolls at an angle therewith for self-feeding of the mandrel upon rotation thereof, said mandrel being rotatable in one direction to move said rolls into an expanded position, a slotted, exteriorly threaded, internally splined housing concentric with a prolongation of the axis of said cage, bearing means securing said housing and cage together rotatably and against axial relative movement, said housing having a plug splined therein for rotation therewith, said plug having an end portion of said mandrel secured therein for rotation with the housing, a collar threaded on said housing, said housing and mandrel being rotatable in one direction to self-feed said mandrel and expand said rolls, and means passing through said slotted housing secured to said plug and engageable by said collar for locking the axial movement of said mandrel secured to said plug with respect to said cage in the other direction of rotation of said housing and mandrel.

8. In a tube expander, a cage having a plurality of radially movable rolls therein, a flanged sleeve around an end of said cage, a housing concentric with a prolongation of the axis of said cage and sleeve and having a cap secured on one end thereof and extending over said flanged sleeve to secure said housing and cage against relative axial movement, bearing means between said sleeve and cap for relative rotational movement of said cage and housing, a tapered axially movable mandrel extending axially through said cage and sleeve into said housing and in contact with said rolls for movement thereof into expanded and contracted positions, the rolls and mandrel being set at a self-feeding angle for the mandrel, first means carried by the housing movable axially with the mandrel engaging with and securing an end portion of the mandrel in the housing, and other means carried by said housing engageable with said first means to secure said mandrel and first means against axial movement in one direction, said mandrel being rotatable with said housing in one direction of rotation to move said rolls to an expanded position, said mandrel and housing being rotatable in the opposite direction of rotation in the expanded position of the rolls and engaged position of said first means with said other means and in which engaged position said cage and mandrel are locked against relative axial movement.

9. In a tube expander, a cage having a plurality of rolls therein, a tapered axially movable mandrel passing through said cage in contact with said rolls at a self-feeding angle therewith for movement of said rolls to expanded and contracted positions, a housing secured to an end portion of said mandrel in alignment with said cage for rotational movement of said mandrel and housing as a unit in both directions of rotation thereof, and means including a bayonet lock securing said housing and cage in an expanded position of the rolls against relative axial movement in the direction of rotation of said housing and mandrel which would normally self-feed said rolls to a contracted position.

10. In a tube expander, an exteriorly threaded cage having a plurality of rolls therein, a tapered axially movable mandrel passing through said cage in contact with said rolls at a self-feeding angle therewith for movement of said rolls to expanded and contracted positions, a housing secured to an end portion of said mandrel in alignment with said cage for rotational movement of said mandrel and housing as a unit in both directions of rotation thereof, a stop member on said cage between said rolls and housing for engagement with a fixed stop, and means including a bayonet lock securing said housing and cage, in an expanded position of the rolls and an engaged position of said stop member, against relative axial movement in the direction of rotation of said housing and mandrel which would normally self-feed said rolls to a contracted position.

11. In a tube expander, a cage having a plurality of

rolls therein, a tapered axially movable mandrel passing through said cage in contact with said rolls at a self-feeding angle therewith for movement of said rolls to expanded and contracted positions, a housing secured to an end portion of said mandrel in alignment with said cage for rotational movement of said mandrel and housing as a unit in both directions of rotation thereof, and locking means releasably securing said housing and cage in an expanded position of the rolls against relative axial movement in the direction of rotation of said housing and mandrel which would normally self-feed said rolls to a contracted position.

12. In a method of securing a tube in the second of opposed tube sheets, a first end of which has been secured in a first tube sheet, the method comprising expanding a tool into contact with the second end of the tube only at a location adjacent the interior face of the tube sheet and while expanding the tool tensioning the tube between sheets, expanding the tool further into contact with the tube to cause the tube to be expanded firmly into engagement against the tube seat at said location only, the flow of metal of the tube upon engagement of the tube and seat offsetting the initial tensioning, and thereafter rolling the remaining portion of the tube firmly against the tube seat, said rolling being from the interior face of the sheet outwardly.

13. In a method of securing a tube in the second of opposed tube sheets, a first end of which tube has been secured in a first tube sheet, the method comprising inserting a self-feeding tube expander into the second end of the tube which end is itself freely fitted in the second tube sheet, the expander being inserted for expansion only at a location adjacent the interior face of the sheet, actuating the expander into contact with the tube to cause the expander to tend to self-feed into the tube, restricting the limit of movement of the expander into the tube to the location adjacent the interior face while continuing the actuation thereof to cause the expander to engage the tube only at said location and the tube to be drawn into tension between tube sheets by the reaction of the expander on the tube, continuing the actuation of the expander to cause the tube to be expanded firmly against the tube seat at said location, the engagement of the tube with the tube seat occasioning offsetting of the initial tensioning, and thereafter expanding the remainder of the tube into engagement with the tube seat.
